COLLECTION-DRAFT, &c., SHEET.

Specification of Letters Patent.

Patented July 21, 1914.

Application filed May 9, 1913. Serial No. 766,514.

To all whom it may concern:

Be it known that I, HERBERT L. PRICE, residing at Baltimore city, State of Maryland, have invented a new and Improved 5 Collection-Draft, &c., Sheet, of which the following is a specification.

The invention has for its object to provide a sheet of related forms including a collection "draft", a letter of "advice to attorney" and a letter of "instructions to bank" attached thereto, the letter of "instructions to bank" being adapted to advise the bank as to the course it should pursue in the event that the "draft" is not paid 10 when presented, while the letter of "advice to attorney" is designed to instruct the attorney as to the course to pursue when the bank turns over the "draft" to the attorney for collection; the sheet also contains 15 a form "bonding notice" that is directed to the bonding company and is designed to advise such company when the "draft" is not paid and is handed by the bank to the attorney; the sheet also contains 20 a stub form on which retained data is collected, identifying the transactions, etc., and this stub form is adapted to remain in the book in which the sheets are bound as a permanent record.

25 The invention also includes a second sheet on which is contained a duplicate copy of the "draft"; the letter of "advice to attorney" and in place of the letter of "instructions to bank" there is contained in relatively the same location, a "draft notice" directed to the debtor, the "draft notice," the copy of the "draft" and the copy of the letter of "advice to attorney" being designed for transmittal to the debtor at the time the 30 "draft" is forwarded to the bank; the second sheet also contains a copy of the "draft notice"; this form also containing in place of the heading of the original "draft notice," instructions regarding the sending of the copy to the bonding company for 35 endorsement by them and return as a receipt; the second sheet also has a space corresponding to the stub of the original sheet. All of the forms of the original and second sheet 40 contain suitably located "filling in" spaces, in which writing is adapted to be made to fill out the forms; and although the forms are not identical in their printed matter, the "filling in" spaces of the second sheet correspond exactly in location and are adapted 45 to receive the same written matter as are those of the original sheet, thus by placing a carbon paper between the original and second sheet, the entries made on the original sheet forms will be manifolded or transferred to the second sheet forms and both sets of forms will be simultaneously filled out.

In order to facilitate matters, each of the sheets (the original and second sheet) are provided with correspondingly located division or separation spaces to separate the sheet into two vertical sections, the original sheet also having a dividing space or line at which the "instruction to bank" is adapted to be detached from the letter of "advice to attorney" and the "draft" before sending the latter to the attorney. The other section of the original sheet is also provided with a detaching space or line whereby the "bonding notice" can be separated from the stub, while the second sheet is provided with a separating space or line, by means of which the entire sheet can be removed from the book.

The primary object of the invention is to provide a set of original and second or transfer sheets with their "filling in" blanks or spaces so arranged that the single act of writing in on the original sheet will, by the interposition of a carbon sheet, serve to transfer the entry to the "filling in" spaces of the second sheet, certain of the second sheet forms being duplicates of the correspondingly located original sheet forms, while others of the second sheet forms are necessarily duplicates of the correspondingly located original sheet forms only in their "filling in" spaces or blanks, thus reducing the labor necessary in filling in the required data on both the original and second sheet forms.

More subordinately, the invention includes those novel features of construction, arrangement of forms and coöperation between the same, as will be first fully described and then be specifically pointed out 100 in the appended claim, and illustrated in the accompanying drawings, in which:

Figure 1, is a perspective view of a book of forms embodying the invention. Fig. 2 is a plan view of the original entry sheet. Fig. 3 105 is a plan view of the second or transfer entry sheet. Fig. 4 is a reverse plan view of the original entry sheet.

In the drawings, A designates the original entry sheet and B the second or transfer 110 entry sheet.

Referring more particularly to Fig. 2 of the drawings, it will be noticed that the original entry sheet contains in vertical order a letter of "instructions to bank" 1, a letter of "advice to attorney" 2, and a "draft" 3, a "bonding notice" 4 and a "stub" 29.

The form 1 contains blank spaces 5 in which the name and address of the debtor may be written. It also contains a blank space 6 for the name or names and address 13 of the holder of the bond of the bonding company. The "instructions to bank" form 1 also includes a space 7 in which the amount involved may be inserted.

The letter of "instructions to attorney" 15 form includes blank spaces 8 for the name and address of the attorney and blank spaces 9 for the name and address of the holder of the bond of the bonding company.

The letter of "instructions to bank" is in 20 the form of a printed letter informing the bank of the course to pursue in the event that the "draft" is paid, and also informing them as to what course to take in the event that the "draft" is not paid.

The letter of "advice to attorney" is in 25 the form of a printed letter telling the attorney what action to take when the bank turns the "draft" over to him.

The "draft" form 3 is in the usual form, 30 and contains the usual blanks 10 for the amount involved in figures, the blank 11 for the insertion of the date, the blank 12 for the insertion of the time at which the "draft" is payable, the blank 13 for the insertion 35 of the name of the bank at which it is payable, the blank 14 for the insertion of the place of business of the bank, the blank 15 for the insertion of the written amount involved, the blank 16 for the name 40 and address of the bond holder and the blank 17 for the name and address of the debtor.

The "bonding notice" is in the nature of 45 a form letter or notice to the bonding company and contains the "filling in" spaces or blanks 18 for the debtor's name, 19 for the amount involved, 20 for the name of the attorney, 21 for the address of the attorney, 22 for the date on which the matter 50 was turned over to the attorney, 23 for the name and address of the holder of the bond and 24 for the date on which the notice is sent to the bonding company.

The "stub" may contain any desired form 55 data in which a memorandum of the transactions may be entered.

The forms of the second sheet correspond 60 in location to those of the first or original sheet and corresponding "filling in" spaces on the second sheet are numbered on the drawing with the same numbering as the original sheet plus the index letter "a"; thus the "draft notice" corresponding in location to the "instructions to bank" is numbered 1^a, the copy of the letter of "advice to attorney" 2^a, the copy of the "draft" 3^a, the copy of the "bonding notice" 4^a and the space corresponding to the "stub," 29^a. The "filling in" spaces of the various forms are also numbered to correspond with the original sheet plus the index letter "a." 70

The "draft notice" form, it will be observed, corresponds to the "instructions to bank" form only in the purpose and location of the "filling in" space 5^a—6^a—7^a. 75 The printed matter on the "draft notice" form is a letter notifying the debtor that a draft has been made on him with instructions to the bank to hand the same, if unpaid, to the attorney, the copy of the letter of "advice to attorney" and the copy of the "draft" being a true copy of the originals.

The original and second sheets each have a vertical separating space or tearing line 85 26—26^a, by means of which the sheet may be separated into two vertical parts, one of which (the original sheet section) is sent to the bank when filled in, while the other, (the second sheet section) is mailed at the 90 same time to the debtor.

In the event that the bank notifies the bondholder that the draft has not been paid, and that the same has been turned over to the attorney, the bond holder then fills in 95 the notice to the bonding company on the original sheet, tearing it out along the tearing space or line 27—28 and sending it together with the second sheet copy 4^a (which is adapted to be detached along the detaching line 28^a) to the bonding company. The bonding company then indorses the second sheet form 4^a and returns it to the bond holder as a receipt. 100

From the foregoing it will be seen that 105 the forms afford a convenient means of transacting business and of making the necessary entries or filling in necessary blank spaces with the least possible effort on behalf of the user (the holder of the bond). 110

From the foregoing taken in connection with the drawings, the construction, uses and advantages of the invention will be clear to those skilled in the art. 115

What I claim is:—

An original entry sheet having a main dividing portion at which the sheet may be separated into two sections, each of said sections having a plurality of printed forms, each section having a dividing portion at 120 which one of the forms of a sheet section may be separated from the remainder, combined with a second or transfer entry sheet having a dividing portion corresponding in relation and location to that of the original sheet at which said second sheet may be divided into two sections that correspond in location to the sections of the original sheet, those of said second sheet having a plurality 125 of forms like in number to those of the cor- 130

responding sections of the original sheet, certain of said forms of the second sheet being duplicates of those of corresponding location in the original sheet and at least one 5 of said second sheet section forms being of a different nature than the one of corresponding location on the original sheet, said forms of the original and second sheets having correspondingly located "filling in" spaces 10 whereby the entries on the original sheet may be transferred by manifolding to the second sheet to simultaneously fill in the spaces of the second sheet forms as the corresponding spaces of the original sheet forms are filled in.
